ELECTRIC DISCHARGE TUBE

Adrianus Johannes Wilhelmus Marie van Overbeek, Eindhoven, Netherlands, assignor, by mesne assignments, to Hartford National Bank and Trust Company, Hartford, Conn., as trustee

Application April 22, 1946, Serial No. 663,822
In the Netherlands February 15, 1943

Section 1, Public Law 690, August 8, 1946
Patent expires February 15, 1963

3 Claims. (Cl. 250—174)

1

This invention relates to an electric discharge tube having a secondary-emission electrode i.e. an electrode which, when being struck by a primary electron having a sufficient velocity, emits a plurality of secondary electrons. Such an electrode is also called "auxiliary cathode."

The dislodged secondary electrons must be drawn through the field between the anode and the auxiliary cathode to the anode. Consequently this field should have a definite value, notably at the surface of the auxiliary cathode, in order to prevent the production of a troublesome space charge in regard to the secondary-emission electrode. In ordinary secondary-emission tubes, in which use is made of one or of two multiplication stages at the most, the potential difference between the anode and the preceding auxiliary cathode usually does not exceed 50 volts in order that the voltage to be applied to the tube should not become too high. Consequently, in order that the field between the anode and the auxiliary cathode shall have a sufficient value the distance between them must be small.

It is already known to design the auxiliary cathode as a netting of metal gauze on to which an activating agent is applied. In this case the anode is located close behind the netting. This has the drawback that a large part of the primary electrons steadily passes through the netting and reaches the anode without having dislodged any secondary electrons. Again it is known to place the flat secondary-emission electrode and the flat anode at a fairly large angle with respect to one another. In this event the auxiliary cathode lies in the path of the primary electrons and the anode is located at the side. As a rule, however, the field is not sufficient to prevent space charges.

In order to make the field between the two electrodes stronger it is necessary make the angle very small. This has the drawback, however, that in the case of the anode voltage being a little too high which may, for instance, occur in the event of feeble control or for other reasons, a part of the primary electrons is moving directly to the anode without having dislodged secondary electrons from the auxiliary cathode. Owing to the high anode voltage the paths of the primary electrons are curved to such a degree that these electrons find their way to the anode instead of to the auxiliary cathode. This detrimental effect also occurs when by providing stops which are apertures or useful openings of a lens, usually adjustable by means of a dia-

2

phragm, the beam of primary electrons at the normal anode voltage solely reaches the auxiliary cathode. Narrowing of the stops would result in that at the same voltage the current from the cathode to the auxiliary cathode becomes much too small.

The invention has for its purpose to cure these drawbacks. To this end the anode of a secondary-emission tube, in which the anode is located outside the paths of the primary electrons, is curved and faces with its convex side the secondary-emission electrode in such a manner that the distance between the anode and secondary-emission electrode decreases with an increase in distance from the primary cathode. Of course, the distance between them should be small and the strongest curvature of the anode lies at least approximately in the plane of the paths of the primary electrons. Consequently, the anode is curved in the same sense as the paths of the primary electrons, as a result of which these electrons, notwithstanding the increase in anode voltage, do not so easily find their way to the anode.

25 In a particularly suitable form of construction the secondary-emission electrode is curved in the same sense as the anode. In this case the distance between the two electrodes becomes as small as possible throughout the surface, as a result of which no trouble is experienced in regard to the auxiliary cathode even with a possible small potential difference between the anode and the auxiliary cathode. Another advantageous form of construction of a tube according to the invention comprises two cathodes and two anodes but only one secondary-emission electrode whose active parts are curved towards the associated anodes. The tube is particularly suitable for use in so-called push-pull arrangement, since the inlet of the auxiliary cathode does not carry a high-frequency voltage with respect to the cathode.

30 In order that the invention may be clearly understood and readily carried into effect it will now be described more fully with reference to the accompanying drawing, given by way of example.

Figure 1 is a cross-section of the electrode system of a discharge tube comprising an auxiliary cathode which is placed at a small angle relatively to the anode.

Figure 2 is a cross-section of the electrode system of a tube, in which the convex side of the anode faces the auxiliary cathode.

Figure 3 represents the electrode system of a tube having two cathodes, two anodes and one secondary-emission electrode.

Figure 1 is a horizontal section of the electrode system in which 1 denotes the cathode, 2 the control-grid and 3 the screen-grid. The electrons issuing from the cathode are drawn to the auxiliary cathode 4. The paths of the electrons are indicated by full lines and arrows. The secondary electrons dislodged from the auxiliary cathode are drawn towards the anode 5. The voltage set up at the screen-grid amounts to 150 relatively to the cathode, the voltage of the auxiliary cathode amounting to 250 and that of the anode to 300. The function of the screens 6 is to convey the primary electrons, at the normal anode voltage, exclusively to the auxiliary cathode. When the anode voltage becomes too high for some reason, for instance only 10 or 15 volts too high, the paths of the primary electrons are curved so much stronger that the slower of them find their way directly to the anode. This is represented by dotted lines.

In Figure 2 the arrangement corresponds to that in Figure 1. In this case, however, the convex side of the anode 5 faces the auxiliary cathode so that the primary electrons moving in curved paths do not easily find their way to the anode even with an increased anode voltage.

Figure 3 is a horizontal cross-section of a push-pull tube. The tube comprises two electrode systems having the auxiliary cathode 4 and the activated parts 7 in common. The anode associated with each cathode is divided into two parts similarly to the secondary-emission electrode 4. It is also possible, however, to design the secondary-emission electrode and the anode in such a manner that they have circular symmetry normally to the plane of the drawing, so that they are undivided. In this event the cathode and the grids must extend with their axis parallel with the axis of the secondary-emission electrode. The activated parts of the auxiliary cathode are curved in the same sense as the two opposite anodes. As a result thereof of the distance between the said electrodes may be very small so that the auxiliary cathode experiences practically no trouble from space charge even when the potential difference between them is small. The two anodes 5 are interconnected through the primary winding 8 of an output transformer having a secondary winding 9 to which the load resistance may be connected. The anode voltage is supplied to the centre tapping 10 of the primary winding of the output transformer.

What I claim is:

1. An electron discharge tube comprising means to generate a stream of primary electrons directed in a given path, a secondary emissive electrode having its active surface positioned in the path of the primary electrons to intercept said primary electrons whereby secondary electrons are emitted therefrom, and an anode electrode having a convex electron collecting surface spaced from and facing said secondary emissive electrode, said convex electron collecting surface

being positioned outside of said primary electron stream path and portions thereof remote from said primary electron generating means being spaced closer to said secondary emissive electrode than portions thereof adjacent said primary electron stream generating means.

2. An electron discharge tube comprising means to generate a stream of primary electrons directed in a given path, a secondary emissive electrode having a concave active surface positioned in the path of the primary electrons to intercept said primary electrons whereby secondary electrons are emitted therefrom, and an anode electrode having a convex electron collecting surface spaced from and facing said secondary emissive electrode, said convex collecting surface being positioned outside of said primary electron stream path and portions thereof remote from said primary electron generating means being spaced closer to said secondary emissive electrode than portions thereof adjacent said primary electron stream generating means.

3. An electron discharge tube comprising a cathode source for generating a stream of primary electrons directed in a given path, a secondary emissive electrode having a concave active surface positioned in the path of the primary electrons to intercept said primary electrons whereby secondary electrons are emitted therefrom, a grid electrode interposed between the cathode source and said concave active surface, and an anode electrode having a convex electron collecting surface spaced from and facing said secondary emissive electrode said convex collecting surface being positioned outside of said primary electron stream path and portions thereof remote from said cathode source being spaced closer to said secondary emissive electrode than portions thereof adjacent said primary electron stream generating means the spacing between said secondary emissive electrode and said anode electrode being unobstructed whereby secondary emission from said secondary electrode impinges on the said anode.
